UNITED STATES PATENT OFFICE.

WILLIAM HILDEBRANDT, OF WASHINGTON, DISTRICT OF COLUMBIA, ASSIGNOR TO GASOLINE CORPORATION, OF NEW YORK, N. Y., A CORPORATION OF DELAWARE.

METHOD AND APPARATUS FOR CONDENSING VAPORS.

Application filed March 23, 1921, Serial No. 454,936. Renewed October 6, 1928.

The present invention relates to the condensation of hydrocarbon vapors and more particularly to a method and apparatus for condensing vapors produced in cracking processes.

The vapors produced in the operation of cracking processes ordinarily comprise, in addition to the condensable products desired, a considerable amount of gas and incondensable vapors. If a condenser having a continuous coil of pipe, similar to those ordinarily used in connection with the common type of fire-stills is employed, the condensates which are formed in large quantities in the condenser tend to collect in bodies or pools of liquid which are driven by the rapidly moving gaseous products thru the succeeding portion of the coil and thru the run-down pipes in the form of slugs which are projected into the run-down or collecting tanks at a high velocity. The condensates are thoroughly agitated in their travel thru the condenser and pipe and churn-up the contents of the tanks as they are projected thereinto, thereby throwing a spray of condensates into the gases or atmosphere above the tank, and in this manner, causing an increased loss thru volatilization. When steam is present in the products of the cracking reaction, as is the case in certain processes, a further loss is involved thru the agitation and mixing of the condensate with the condensed steam and the consequent formation of a permanent emulsion.

An object of the present invention is to provide an improved method of condensing vapors from a mixture of vapors and incondensable gases.

Another object of the invention is to provide an improved condenser suitable for use in condensing the products resulting from the cracking of hydrocarbon oils.

A further object of the invention is to provide an apparatus for condensing and separating oils from a mixture of oil, vapors, steam and incondensable gases.

With these and other objects in view, the invention consists in the process and apparatus described in the following specification and defined in the claims.

The various features of the invention are illustrated in the accompanying drawings in which;

Fig. 1, is a view in elevation partly in section of a condenser and separating appara-

tus embodying the preferred form of the invention,

Fig. 2, is a vertical, sectional view of the condenser taken on line 2-2 of Fig. 1, and

Fig. 3, is a plan view of the apparatus illustrated in Fig. 1.

In the present invention, the oil vapors and gases pass, in the initial part of the condensing operation, in a continuous stream thru a continuous, cooled condensing pipe 65 until a considerable quantity of liquid condensate has been formed. The condensates and the partially cooled vapors and gases are thereupon separated into a number of separate streams which flow in parallel thru a number of pipes forming the remaining portion of the condenser. When the condensation of the vapors in these pipes has been completed, the several streams are re-united in a header or chamber in which the 70 liquid condensates collect in a body below the incondensable gases and vapors. The condensed liquid products are continuously withdrawn from the lower part of the cooling header or chamber to a separating tank 75 in which any water contained in the condensate settles to the bottom while the oil is removed from the top of the tank. The residual uncondensed gases are removed from the upper portion of the collecting 80 header to a gas storage or consuming apparatus.

Referring more particularly to the accompanying drawings, the vapors and gases from the cracking or treating apparatus pass 90 to the condenser thru a vapor pipe 10 and enter the upper portion of a pipe or coil 12 submerged in a body of cooling water 13 contained in a condenser box 14. The pipe 12, which is similar to the condenser pipes commonly used in connection with fire-stills, is shown in the accompanying drawings in the form of two tiers of flat coils connected in series by means of a connecting pipe 16, in such a manner that the oil vapors pass in a 100 single, rapidly flowing stream thru the entire pipe. In passing thru the pipe, the oil vapors are cooled and a considerable portion of them condensed.

The condensates and uncondensed vapors 105 are withdrawn from the lower end of the coil 12 thru a connecting pipe 18 to a header 20 in which the speed of travel of the vapors and condensates is reduced to permit the condensate to separate from the uncondensed 110

vapors and gases and collect as a body 21 in the lower part of the header. From the header 20, the vapors and condensates are distributed to a number of separate condensing pipes 22 thru the upper portion of which the vapors pass while the condensates flow as separate streams 23 in the lower portions. The condensing pipes 22 are slightly inclined in a uniform downward direction 10 to a collecting header 24 to cause the liquids to flow rapidly and continuously thru the lower portion of the pipes and to prevent the pocketing of the condensates and the formation of bodies of liquid and the consequent 15 propulsion of these liquids thru the pipes at a high rate of speed. The condensates and vapors collecting in the header 24 fall thru a connecting pipe or nipple 26 to a lower distributing header 28 from which the vapors and liquids are redistributed to a 20 second set of pipes 30 arranged similarly to the pipes 22 and preferably inclined slightly downwardly from the header 28. As the vapors and liquids flow thru the pipes 30, the condensation of the condensable portion 25 of the remaining vapors is completed. From the pipes 30 the resulting condensate and vapors enter a lower collecting header 32 in the lower part of which the condensates 30 collect in a pool or body 33 above which the gases pass to a number of upright outlet pipes 34. It will be understood that in some cases but one set of distributing and collecting headers and connecting pipes may be 35 necessary and that the form of the coil and the form and arrangement of the distributing header connecting pipe and collecting header may be varied to suit different conditions. The condensate collecting in the 40 lower part of the header 32 is withdrawn thru draw-off pipe 36 to a separating tank 38 in which the water formed by the condensation of steam contained in the vapors from the cracking operation is separated 45 from the oil condensate.

The pipe 36 extends into the tank 38 for a short distance and has an upturned foraminous portion 40 which permits the water and oil to gradually escape from the pipe in 50 small, slowly moving streams, avoiding eddy-currents and insuring a quicker and more uniform separation of the water from the oil. The oil collecting above the water in the upper part of the separating tank 55 flows upwardly thru an outlet pipe 42 and thru a look-box 44 to a run-down pipe 46 leading to an oil run-down or collecting tank. The water settles to the lower part of the tank 38 and is removed thru a pipe 60 48, which extends upwardly to a slight distance below the level of pipe 42. Since the pipe 48 is filled with water and overflows at a lower level than the pipe 42, water will escape thru the pipe 48 rather than thru the 65 pipe 42 even though the tank should become

filled with water, and the passage of water into pipe 46 is therefore automatically prevented. The water in pipe 48 will, however, over-balance a column of oil extending from the level of the entrance to pipe 48 to the top 70 of pipe 42 and accordingly oil will pass thru the pipe 42 rather than thru pipe 48 even if the tank 48 should become completely filled with oil from the level of the inlet pipe 48. A complete and thorough separation of the 75 oil and water is accordingly insured regardless of the proportions of the two liquids produced under different operating conditions.

The gases withdrawn from the collecting 80 and separating header 32 thru the separating pipes 34 are collected in a header 50 located above the condenser box 14. From the header 50, the gases are withdrawn thru a pipe 52 and gas meter 54 to a pipe 56 which 85 leads to a gas storage or consumption system.

In the invention above set forth, the gases and vapors pass thru the initial portion of the condenser at a comparatively high rate of speed and thereby obtain the high degree 90 of heat conductivity involved in the rapid passage of gases while in the latter portion of the condenser, in which considerable amounts of liquid are present, the speed of travel is reduced and the pocketing of 95 liquids and gases is avoided. The invention provides an efficient method and apparatus by which the gases and liquids produced in the condensation of a mixture of various vapors and gases may be rapidly separated 100 and avoids the losses involved in the operation of the condensers heretofore used. It will be apparent that various changes may be made in the form of the apparatus without changing the essential features of the 105 invention.

Having described the invention, what is claimed as new is:—

1. A condensing apparatus which comprises a continuous coil, a distributing 110 header connected to said coil, a collecting header at a lower level than said distributing header, pipes connecting said headers, means for cooling said pipes and coil, a gas header above said collecting header, pipes 115 connecting said gas header to the upper part of said collecting header, a liquid draw-off pipe from said collecting header, a separating tank, an oil draw-off pipe from the upper part of said tank, and a water draw-off pipe extending from the lower part of 120 said separating tank to a level slightly below the level of said oil draw-off pipe.

2. A condensing apparatus which comprises a continuous coil, a distributing 125 header connected to said coil, a collecting header at a lower level than said distributing header, pipes connecting said headers, means for cooling said coil and said pipes, a gas collecting header above said collecting 130

header, pipes connecting said gas collecting header to the upper part of said lower header, a separating tank, a liquid draw-off pipe from said lower header having a portion extending into said tank, said portion being foraminous, liquid draw-off pipes leading from the lower and upper portions of said draw-off tank, the lower of the draw-off pipes coming to a level slightly below the 10 level of the second draw-off pipe.

3. A method of condensing vapors from a mixture of gases and vapors which comprises passing said vapors and gases thru a long passage, cooling said vapors and condensing a portion of said vapors, dividing 15 said stream of vapors and condensates into a number of independent streams, cooling said streams and condensing the remaining vapors from said streams, separating said 20 condensates from said residual gases and vapors in said separate streams, collecting the residual gases and condensates and separately withdrawing said gases and said condensates.

25 4. A method of condensing vapors from a mixture of gases and vapors which comprises passing said vapors and gases in a stream at a rapid rate cooling said stream, separating said stream into separate streams, 30 passing said separated streams at a slower rate of speed and cooling said separate streams, collecting the condensates from said separate streams into a body, withdrawing the residual gases from said body of liquid 35 and separating the water from the oil in said liquid.

5. A condenser for condensing a mixture of gases and vapors which comprises a condenser box, a continuous pipe in the upper 40 part of said condenser box, a distributing header into which said pipe leads, a collecting header at a lower level than said distributing header, pipes connecting said headers, means for withdrawing gases from the upper part of said collecting header, 45 means for withdrawing liquids from said collecting header and means for separating the oil and water withdrawn from said header.

50 6. A condensing apparatus which comprises a continuous coil, a header connected to said coil, pipes connected to said header and extending in a slightly downward direction, and cooling means for said coil and said pipe.

55 7. A condensing apparatus which comprises a continuous coil, a distributing header connected to said coil, a collecting header at a lower level than said distributing header, pipes connecting said headers and means for cooling said pipes and coil.

8. A condensing apparatus which comprises a continuous coil, a distributing header connected to said coil, a collecting header at a lower level than said distributing header, 65 pipes connecting said headers, means for cooling said pipes and coil, a gas receiving header above said collecting header and pipes connecting said gas receiving header to the upper part of said collecting header. 70

9. A condensing apparatus which comprises a continuous coil, a distributing header connected to said coil, a collecting header, pipes connecting said headers, said pipes being inclined downwardly from said 75 distributing header to said collecting header and means for cooling said pipes and coil.

10. A condensing apparatus which comprises a condenser box, a continuous coil in the upper part of said condenser box, a distributing 80 header connected to said coil, a collecting header, pipes connecting said distributing header to said collecting header, said pipes being inclined slightly downwardly from said distributing header to said 85 collecting header.

11. A condenser which comprises a condenser box, a continuous coil in the upper part of said condenser box, a distributing header positioned below and connected to 90 the lower end of said coil, a collecting header at a lower level than said distributing header and pipes connecting said headers, said pipes being slightly inclined downwardly towards said collecting header. 95

12. A condenser which comprises a condenser box, a continuous coil in the upper part of said condenser box, a distributing header connected to said coil, a collecting header at a lower level than said distributing 100 header and pipes connecting said headers, said pipes having a uniform, gradual slope towards said lower header.

13. A condenser which comprises a condenser box, a continuous coil in the upper 105 part of said condenser box, a distributing header connected to said coil, a collecting header, pipes connecting said distributing header to said collecting header, a second distributing header positioned below said 110 collecting header and connected to said collecting header, a lower collecting header, pipes connecting said lower distributing header to said lower collecting header, means for withdrawing liquid from the 115 lower portion of said lower collecting header, and means for withdrawing gas from the upper portion of said lower collecting header.

In testimony whereof, I affix my signature. 120

WILLIAM HILDEBRANDT.
